Read Viemeister, Yellow Springs, Ohio, assignor to The Huffman Manufacturing Company, Dayton, Ohio, a corporation of Ohio

Application June 30, 1955, Serial No. 36,770

Term of patent 7 years

(Cl. D90—1)

FIG-1

FIG-2

FIG-3

Fig. 1 is a perspective view of a bicycle radio embodying my new design;

Fig. 2 is an enlarged elevational view of the right hand side of the housing and antenna member drawn in Fig. 1, and

Fig. 3 is a similar view of the left hand side thereof.

The sides not shown on the battery case are similar to those shown and the top surface thereof is plain.

The fragmentary portions of a bicycle shown by means of broken lines are disclosed only for purposes of illustration.

I claim:

The ornamental design for a bicycle radio, substantially as shown and described.
